UNITED STATES PATENT OFFICE.

MASAICHI AOYAMA AND JUICHI HIGASHINO, OF SACRAMENTO, CALIFORNIA.

LAMP-EXTINGUISHER.

1,210,256.

Specification of Letters Patent. Patented Dec. 26, 1916.

Application filed July 5, 1916. Serial No. 107,666.

To all whom it may concern:

Be it known that we, MASAICHI AOYAMA and JUICHI HIGASHINO, citizens of the United States, residing at Sacramento, in the county of Sacramento and State of California, have invented new and useful Improvements in Lamp-Extinguishers, of which the following is a specification.

This invention relates to improvements in lamp burners and especially with reference to improvements in means to automatically extinguish a lamp when the same is moved from an upright position, the object of the invention being to provide improved extinguishing devices of this character which are cheap and simple in construction and which may be readily installed in an ordinary lamp burner.

The invention consists in the features of construction, combination, and arrangement of devices, hereinafter fully described and claimed, reference being had to the accompanying drawings, in which:—

Figure 1 is a sectional view of a lamp burner provided with extinguishers constructed and arranged in accordance with our invention. Fig. 2 is a similar view at right angles to Fig. 1. Fig. 3 is a horizontal sectional view. Figs. 4 and 5 are detail views.

In the lamp burner here shown, the cap is indicated at 1, the gallery at 2, the base at 3, and the wick tube at 4. In accordance with our invention, we provide a pair of extinguishing hoods 5, 6, which are arranged at opposite sides of the wick tube, are adapted to close thereover to extinguish the flame, and are respectively pivotally mounted in the burner as at 7, 8. Wires are employed as pivots for the extinguishing hoods which are passed through openings in the ends of the hoods and have their ends bent downwardly and secured on the perforated portion 9 of the burner. Normally the hoods are tilted outwardly and bear at their lower outer sides on the perforated portion of the burner. When the lamp is inclined in either direction at right angles to the pivot axes 7, 8, of the hoods, one of the hoods will be overbalanced and will move to closed and

extinguishing position as indicated in dotted lines as in Fig. 1 and as will be understood.

To cause the hood 6 to move to extinguishing position in the event that the lamp should be inclined in either direction parallel with the pivotal axes 7, 8, we provide a rocker 10 which is made of wire, is mounted at the ends 11, in bearings 12 secured on the perforated portion 9 of the burner and has a depending arm 13 provided with a weight 14 and also has a laterally extending arm 15 which engages under one end of the extinguishing hood 6 at a point spaced a suitable distance from the pivot wire 8. While the lamp is in an upright position, the weight 14 holds the arm 15 in lowered position, but should the lamp be inclined in one direction, parallel with the pivotal axes 7, 8, the weight will cause the rocker to turn and also cause the arm thereof to move upwardly and thereby close the extinguishing hood 6. A similar rocker 16 is provided for the extinguishing hood 5, its arm extends in the opposite direction from the arm 15 and hence, when the lamp is inclined in the reverse direction, the weighted rocker 16 will close the extinguishing hood 5, as will be understood.

Having described the invention what is claimed is:

In combination with a lamp burner, having a perforated base portion, and also having a pivotally mounted extinguishing hood, a rocker element comprising an axle portion, a depending weighted arm, and a substantially horizontal operating arm, and bearings on said perforated portion of the burner and in which the axle portion of said rocker is mounted, the weighted arm of the rocker extending downwardly from said perforated portion, the arm of said rocker slidably engaging under the hood and the axle portion of said rocker being arranged at right angles to the pivot axis of the hood. 95

In testimony whereof we affix our signatures.

MASAICHI AOYAMA.
JUICHI HIGASHINO.
